UNITED STATES PATENT OFFICE.

CHARLES M. ABERCROMBIE, OF BRIDGEPORT, CONNECTICUT, ASSIGNOR TO THE
SINGER MANUFACTURING COMPANY, A CORPORATION OF NEW JERSEY.

SEWING-MACHINE.

1,338,064.

Specification of Letters Patent. Patented Apr. 27, 1920.

Application filed June 20, 1916. Serial No. 104,653.

To all whom it may concern:

Be it known that I, CHARLES M. ABERCROMBIE, a citizen of the United States, residing at Bridgeport, in the county of Fairfield and State of Connecticut, have invented certain new and useful Improvements in Sewing-Machines, of which the following is a specification, reference being had therein to the accompanying drawings.

10 This invention relates to improvements in sewing machines employing a needle having both reciprocating and lateral movements as in the stitching of hem-stitch seams and has for its object to simplify and improve 15 the means employed for giving to the needle its stitch-forming movements.

In the accompanying drawings illustrating the invention, in the several figures of which like parts are similarly designated, 20 Figure 1 is a view in elevation of a hem-stitch sewing machine equipped with the present invention, the head of the arm-bracket being shown partly in section to better illustrate the means employed for 25 giving to the needle its reciprocating movements. Fig. 2 is a front end elevation of Fig. 1. Figs. 3, 4, 5 and 6 are views in elevation of the needle vibrating bar, the tubular needle carrying bar, the needle vibrating bar guide bracket and the needle vibrating bar yoke, respectively.

The invention is herein shown and will be described in connection with so much of one variety of Singer commercial hem-stitch sewing machines as is deemed sufficient for an understanding of its application, and is intended to comprise improved means over that represented by U. S. Patent No. 724,233, March 31, 1903, to the present inventor for controlling the stitch-forming movements of the needle.

1 represents the sewing machine bed-plate upon which is mounted the bracket-arm comprising the arm-bracket 2 and standard 3, 4 the main- or needle-bar driving shaft mounted in suitable bearings formed in the bracket-arm and provided with the band-wheel 5, belt-pulley 6 (shown in dotted lines only), gear member 7 and shaft flange 8. 50 9 denotes the needle-thread take-up, 10 a link in the train of connections, common to the commercial machine previously referred to, for transmitting from the main-shaft reciprocating movements to the needle 55 11, and 12 the spring depressed cloth-presser

carrying bar which, in practice, is provided with a suitable cloth-presser (not shown).

13 represents the needle vibrating bar, 14 the needle vibrating bar tubular guide, 15 the tubular needle carrying bar and 16 the needle vibrating bar oscillating yoke. To assemble the parts 13, 14, 15 and 16, as in Figs. 1 and 2, the yoke 16 is positioned between the lugs 17 and 18 of the head 19 of the arm-bracket and in line with the openings 21 and 22 in said lugs when the bar 15, after having removed the needle-bar actuating collar 23, is passed up through the opening 24 in the yoke and the collar positioned and secured as in Fig. 4, followed by positioning the guide 14 in the opening 25 of the yoke with the lugs as 26 tracking the groove 27 in said yoke when the bar 13 is passed up through the opening 28 in the bar 15 and through the opening 29 in the guide 14, after which the elements 13, 14 and 15 are moved downward sufficient to secure said guide on to the bar 13 by tightening the screws, as 30, the guide being positioned with respect to the collar 31, suitably secured on the lower end of the bar 13 and later to be referred to, to hold the bar 15 against lengthwise movement on the bar 13, when the lower end of the link 10 is operatively connected with 85 the bearing 32 on the collar 23, as best illustrated in Fig. 1.

The gear member 7 carried by the main-shaft co-operates with the gear member 33 forming a part of the needle vibrating cam 34 provided with a cam-groove 35, said gear and cam member being mounted to rotate on a shaft 36 suitably secured in the standard 3 of the bracket-arm, the ratio of said gears being as 1 to 3, the same as 95 is common to machines of the present class.

37 denotes the pitman actuating-lever provided with a fulcrum-pin 38 journaled in a bushing 39 suitably secured in the bracket-arm, a collar 40 and set-screw 41 (shown in dotted lines only) acting to secure said fulcrum pin against accidental endwise movement, the lever 37, at its lower end, being provided with a stud 42, and cam-roller 43 (the elements 42 and 43 being 100 shown in dotted lines only), the latter tracking the cam-groove 35, thus giving to the lever 37 oscillatory movements.

49 represents the pitman bracket adjustably secured by screw 50 in a guide-way 51 110

formed in the lever 37, said bracket having secured to it by the suitably secured cap 52 one end of a spiral spring 53 whose opposite end is suitably secured in the pitman 54, the front end of the latter carrying a like suitably secured spring 55 whose opposite end is secured to the yoke 16 by the suitably secured cap 56, thus transmitting from the cam-groove 35, through the connecting elements pointed out, rocking movements to the yoke 16, the latter transmitting through the guide 14, oscillatory movements to the bar 13.

In the construction of the pitman 54 the spiral springs 53 and 55 are preferably formed with the coils of wire in juxtaposed relationship, and the co-efficient of elasticity of each spring in the direction of its length is such that the resistance to strain is in excess of the capacity of the motive power required to actuate the driven element.

57 represents a pinch collar secured by screw 58 to the lower end of the tubular bar 15, said collar being provided with a bearing stud 59 upon which is pivotally secured by screw 60 a needle carrying bracket 61 into which is suitably secured the needle 11. Into the collar 31 fast on the oscillating bar 13 is secured a driving element comprising pins, as 62, arranged one at one side and the other at the opposite side of the bracket 61, said pins through the oscillatory movements of the bar 13 transmitting lateral movements to the needle 11, thus effecting reciprocal movements of the latter in different paths.

In the present, as in commercial sewing machines for effecting a true hem-stitch figure, the feed-dog 64 is actuated to give to the fabric two feed movements forward and one return feed movement for each hem-stitch figure and the cam-groove 35 of the cam 34 for giving to the needle its lateral movements is constructed and actuated to effect two descents of the needle in like paths and one descent in a different path.

Having thus set forth the nature of the invention, what I claim herein is:—

1. In a sewing machine, in combination, a needle-bar, means for imparting endwise reciprocations to said needle-bar, a needle-carrying bracket sustained by said needle-bar, a needle-vibrating bar arranged telescopically with respect to the needle-bar and projecting beyond the upper end of the lat-

ter, a yoke having spaced bearings of which one bearing is journaled upon said needle-bar and the other bearing is sustained by said needle-vibrating bar, means for vibrating said yoke from said actuating shaft, 60 operative connections between the second-named bearing of said yoke and said needle-vibrating bar for oscillating the latter, and operative connections between the needle-vibrating bar and the needle whereby the oscillatory movements of the former impart bodily lateral movements to the latter.

2. In a sewing machine, the combination with a needle-bar, a needle sustained by said needle-bar, and means for imparting endwise reciprocations to said needle, of a needle-vibrating bar arranged telescopically with respect to said needle-bar and projecting beyond the upper end of the latter, a guide secured upon said needle-vibrating bar 75 adjacent and beyond the end of the needle-bar, a yoke journaled for vibratory movement coaxially with the needle-vibrating bar, means for vibrating said yoke, means provided upon said yoke coacting with said 80 guide whereby vibratory movement of the yoke imparts oscillatory movement to said needle-vibrating bar, and means whereby the oscillating needle-vibrating bar imparts lateral movements to the needle.

3. In a sewing machine, in combination, a needle-bar, a needle-carrying bracket fulcrumed upon said needle-bar, means for imparting endwise reciprocations to said needle-bar, a needle-vibrating bar arranged 90 telescopically within said needle bar, a vibratory yoke journaled coaxially with the needle-vibrating bar, means for vibrating said yoke, a guide secured upon the needle-vibrating bar adjacent and beyond one end 95 of the needle-bar, a driving element secured upon said needle-vibrating bar adjacent the opposite end of the needle-bar coacting with said guide to restrain the needle-vibrating bar against relative endwise movement with 100 respect to the needle-bar, and means provided on said yoke coacting with said guide for oscillating the needle-vibrating bar.

In testimony whereof, I have signed my name to this specification, in the presence of 105 two subscribing witnesses.

CHARLES M. ABERCROMBIE.
